UNITED STATES PATENT OFFICE.

JOSEPH PELT, OF NEWARK, NEW JERSEY.

DESIGN FOR A SWEATER.

Application filed February 1, 1922. Serial No. 485. Term of patent 3½ years.

To all whom it may concern:

Be it known that I, JOSEPH PELT, a citizen of the United States, residing at Newark, in the county of Essex and State of New Jersey, have invented a new, original, and ornamental Design for Sweaters, of which the following is a specification, reference being had to the accompanying drawing, forming part thereof.

The figure in the drawing is a front perspective view of my new design.

I claim:

The ornamental design for a sweater as shown.

JOSEPH PELT.
